UNITED STATES PATENT OFFICE

2,234,093

KEY SHAFT MOUNTING FOR MUSICAL INSTRUMENTS

Charles W. Silver, Elkhart, Ind., assignor to
Buescher Band Instrument Company, Elkhart,
Ind.

Application July 22, 1940, Serial No. 346,843

1 Claim. (Cl. 84—380)

This invention relates to musical instruments and to an improved mounting means for mounting the tubular key shaft on a saxophone, clarinet, oboe, or other musical instrument.

5 An object of this invention is to provide an improved mounting means for a tubular key shaft which is so constructed as to reduce the friction between the stationary shaft and the tubular rock shaft.

10 Another object of this invention is to provide an improved stationary shaft for a tubular key shaft which is so constructed as to permit the use of a lubricant between the ends of the tubular shaft, the stationary shaft being formed in such a manner as to provide a lubricant chamber between the ends of the tubular key shaft.

15 A further object of this invention is to provide a stationary key supporting shaft which is formed with a reduced intermediate part, the opposite end portions of the stationary shaft being in frictional contact with the inner surfaces of the tubular key shaft and the frictional contact between the stationary shaft and the tubular rock shaft being of such length as to 20 eliminate a considerable friction now present between these parts.

25 Embodying the aims aforesaid and others which may hereinafter appear, the invention consists of the novel construction, combination and arrangement of parts as will be more specifically referred to and illustrated in the accompanying drawing, wherein is shown an embodiment of the invention, but it is to be understood that changes, variations and modifications may 30 be resorted to which fall within the scope of the invention as claimed.

In the drawing:

35 Figure 1 is a fragmentary side elevation of a portion of a musical instrument, such as a saxophone, clarinet, oboe, or the like, having an improved key mounting means associated therewith which is constructed according to an embodiment of this invention.

40 Figure 2 is an enlarged fragmentary sectional view taken on the line 2—2 of Figure 1.

45 Figure 3 is a detail side elevation of the stationary key shaft.

50 Figure 4 is a longitudinal section of a modified form of this invention.

55 Referring to the drawing, the numeral 10 designates generally the branch or body of a musical instrument such as a saxophone, clarinet, oboe, or the like and the numeral 13 designates a pad member which is mounted on a pad car-

rying arm or lever 11. The arm or lever 11 is provided at the end thereof opposite from the pad 13 with a sleeve or bushing 12. A pad operating key 14 is connected to the arm or lever 11 by means of a connecting bar 15 which is 5 connected at one end to the arm 16 of the key 14 and at the opposite end is connected to the arm or lever 11 outwardly from the bushing 12.

The arm 16 of the key 14 is provided with a sleeve 17 disposed in axial alignment with the bushing 12. The bushing 12 and the sleeve 17 are rockably mounted as shown in Figure 2 on a solid cylindrical stationary supporting shaft generally designated as 18. The shaft 18 comprises a pair of outer end bearing portions 20 and 21 which are of substantially the same diameter and which are connected together by means of a reduced diameter part 22. Extending from the outer end of the bearing portion 20 is a short part 22a of reduced diameter and which corresponds in diameter to the part 22. The outer end of the bearing portion 21 is formed with a kerf 23. The outer end of the reduced part 22a merges into the inner end of a peripherally threaded stud 24, which is adapted to be threaded into a supporting post 25. The diameter of the stud 24 is less than the bearing portions 20, 21 and greater than the reduced part 22a.

30 The shaft part 21 is extended through a second supporting post 26. In the present instance an intermediate tubular key shaft 27 is disposed about the stationary shaft 18 and is disposed between the bushing 12 and the bushing or sleeve 17. A key 28 is fixed to the shaft 27 adjacent one end thereof and a pad carrying arm 29 is fixed to and extends laterally of the opposite end of the shaft 27. The reduced shaft part 22 in the present instance is disposed wholly 40 within the shaft 27 and between the ends thereof and thus forms a lubricant chamber or reservoir 30.

45 A suitable lubricant such as a light grease or the like may be applied about the reduced part 22 when the shaft 18 is inserted within the bushing 12, tubular shaft 27 and bushing 17. In this manner the larger diameter bearing parts 20 and 21 of the shaft 18 will be lubricated from the chamber 30, the fit between the bearing parts and the tubular shafts or bushings 12, 17 and 27 being such that an excess of lubricant 50 will not leak out.

55 By providing a mounting means for one or more key structures as shown in the drawing,

the rock shafts or bushings will be provided with reduced bearing surfaces on the stationary shafts so as to thus eliminate a considerable amount of friction and in addition by forming the stationary shaft with a reduced intermediate part, a lubricant may be held within one or more of the rock shafts so that the rock shafts may be amply lubricated and eliminate the necessity of removing the stationary shaft in order to apply the necessary lubricant as is at present the case. While I have shown the stationary shaft 18 as having a pair of keys rockably mounted thereon, it will be understood that this same shaft structure may be used with any or all of the tubular rock shafts now forming part of the instrument.

In Figure 4, there is shown a key shaft supporting structure wherein a stationary shaft 31 is mounted between a pair of end posts 32 and 33. The shaft 31 is formed with a plurality of spaced apart cylindrical bearing parts 34, 35, 36, 37, 38, 39 and 40 which are connected together by integral reduced connecting parts. The bearing parts 34 and 35 are connected together by a reduced part 41, and the bearing parts 35 and 36 are connected together by a reduced part 42. Bearing parts 36 and 37 are connected together by a reduced part 43 and bearing parts 37 and 38 are connected together by a reduced part 44. In like manner bearing parts 38 and 39 are connected together by a reduced part 45, and bearing parts 39 and 40 are connected by a reduced part 46.

An intermediate supporting post 47 engages the bearing part 35 and a tubular key shaft or sleeve 48 is rockable on the bearing parts 34 and 35 between the end post 32 and the post 47. A second intermediate post 49 engages the bearing part 37 and a pair of tubular key shafts or sleeves 50 and are disposed between the posts 47 and 49, the shaft 50 being rockable on the bearing parts 35 and 36, and the shaft 51 being rockable on the bearing parts 36 and 37.

A third intermediate supporting post 52 engages the bearing part 39 and a tubular key shaft or sleeve 53 is rockable on the bearing parts 38 and 40 and is disposed between the posts 33 and 52. Key shafts 54, 55 and 56 are disposed in end abutting relation between the intermediate posts 49 and 52. Shaft 54 is rockable on a

portion of bearing part 37 and a portion of bearing part 38. Shaft 55 is a relatively short shaft and is rockable only on bearing part 39, and shaft 56 is rockable on both bearing parts 39 and 39.

The bearing parts 34, 35, 36, 37, 38, 39 and 40 form therebetween lubricant chambers 57, 58, 59, 60, 61 and 62 so that the several rock shafts or sleeves may be properly lubricated. The outer end of the bearing part 34 merges into a part 40 34^a of reduced diameter and from such part 34^a extends a peripherally threaded stud 63 which is threaded into the end part 32^a. The stud 63 constitutes one of the end terminal portions of the shaft 31. The outer end of bearing part 15 40 emerges into a part 40^a of reduced diameter from which extends a smooth stud 49^b arranged within the end post 33. The stud 49^b forms the other end terminal portion of the shaft 31.

It will be apparent from the foregoing that the stationary pivot shaft 31 may be of any desired length and that there may be formed thereon any desired number of bearing parts and reduced diameter connecting parts, and as the length of the shaft 31 increases intermediate 25 supporting posts may be provided to properly support the shaft.

What I claim is:

In combination, in a musical instrument having a tone pipe, a pair of spaced apertured posts secured to said pipe, a rockable tubular key shaft arranged between said posts, a stationary shaft extending through one of said posts and having an end threadedly engaging with the other, said stationary shaft extending through said tubular shaft and being of circular contour in cross section, said stationary shaft formed with a pair of spaced endwise aligned portions of corresponding diameter constituting bearings for the inner face of said tubular shaft and with a portion arranged between and of reduced diameter with respect to the said other portions, said portion of reduced diameter correlating with the aligned ends of the portions of greatest diameter and a part of the inner face of said tubular shaft to provide a lubricant chamber, and said stationary shaft having a kerf in the end thereof opposite from the threaded end.

CHARLES W. SILVER. 50
